UNITED STATES PATENT OFFICE.

CHARLES E. SLOCOMB, OF BOSTON, MASSACHUSETTS, ASSIGNOR TO ALBERT W. W. MILLER, OF SOUTH ORANGE, NEW JERSEY.

SHOE-NAIL.

SPECIFICATION forming part of Letters Patent No. 681,143, dated August 20, 1901.

Application filed May 27, 1901. Serial No. 62,114. (No model.)

To all whom it may concern:

Be it known that I, CHARLES E. SLOCOMB, a citizen of the United States, residing in Roxbury, Boston, county of Suffolk, State of Massachusetts, have invented a certain new and Improved Shoe-Nail, of which the following is a specification.

The purpose of this invention is to produce a nail having an end portion sufficiently flattened to be readily clenched, and yet of sufficient rigidity to withstand compression strains to which it is subjected in being driven, and a penetrating-point which is of sufficient keenness to readily make an entrance, and yet is so formed as not to "turn" in the driving operation when presented to material of considerable hardness. Such nails are primarily intended for use in the manufacture of boots and shoes and are particularly adapted to securing the heels, and when to be so used are preferably formed with a collar, beyond which is a spur or head portion by means of which the top lift of the heel is attached. United States patent of Hart, No. 376,988, dated January 24, 1888, shows a nail of that character, and still other forms have been patented. Nails of this kind are usually made of round-wire stock and the collar swaged or forged into shape, and it is common to provide them with tapering, oval, or awl points. I am also aware that the patent of Estabrook, No. 261,213, dated July 18, 1882, shows a shoe-nail with a point of diamond-like cross-section tapering from the body or shank to the penetrating-point.

In my improved nail the shank may be round, corresponding with the steel-wire stock from which it may be made. The point portion which is to be or may be turned over or clenched is flattened into an elongated diamond-shaped cross-section tapering toward the extreme end or penetrating-point, which is formed by turning the four sides of said tapering diamond-shaped portion toward the axis of the nail at a greater angle than that of the taper, the four inwardly-turned faces uniting or merging into a comparatively keen penetrating-point, and I also prefer in like manner to carry or turn the edges

formed by the more acute angles of the diamond-shaped part toward the axis. Such a nail may be made either by means of dies or cutters, preferably the former. It has all the advantages suggested at the beginning of this specification.

In the accompanying drawings, Figure 1 is an elevation; Fig. 2, an elevation at right angles to Fig. 1; Fig. 3, a view looking at the point of the nail. Fig. 4 indicates the cross-section at the line *s-s* of Figs. 1 and 2.

a represents the shank of the nail, usually and preferably round, and *b* is the flattened tapering diamond-shaped point portion adapted to be turned over and clenched. Its four flat sides 1 2 3 4, sufficiently close to the extreme or penetrating point of the nail, are turned more acutely toward the axis of the nail, as shown at 5 6 7 8, forming a secondary tapering diamond-shaped part of more acute taper and of relatively short length, the sides 5 of which merge into the relatively keen penetrating-point marked *x*. The lines of the more acute angles of the diamond-shaped part *b* are similarly carried inwardly toward the axis of the nail, as shown at *b'*.

In the drawings, which show a shoe-heel nail, *A* is the ordinary collar, and *a'* the spur projecting beyond it for retaining the top lift.

I claim as my invention—

1. A shoe-nail having a tapering diamond-shaped end portion *b*, and a penetrating diamond point formed by the four faces of said portion turned toward the axis of the nail at an increased angle.
2. A shoe-nail having a tapering diamond-shaped end portion *b*, and a penetrating diamond point formed by the four faces of said portion turned toward the axis of the nail at an increased angle, and by the edges forming the more acute angles of the portion *b* also turned toward said axis.

In testimony whereof I have hereunto subscribed my name.

CHARLES E. SLOCOMB.
